UNITED STATES PATENT OFFICE.

JOHN D. KARLE, OF NEWARK, NEW JERSEY, ASSIGNOR TO THE SINGER MANUFACTURING COMPANY, A CORPORATION OF NEW JERSEY.

ATTACHMENT-HOLDER FOR SEWING-MACHINES.

1,192,818.

Specification of Letters Patent. Patented July 25, 1916.

Application filed October 23, 1914. Serial No. 868,226.

To all whom it may concern:

Be it known that I, JOHN D. KARLE, a citizen of the United States, residing at Newark, in the county of Essex and State of New Jersey, have invented certain new and useful Improvements in Attachment-Holders for Sewing-Machines, of which the following is a specification, reference being had therein to the accompanying drawings.

10 This invention has for its object to provide attachment holding means which may be conveniently applied to and removed from the work-plate of a sewing machine and which may be securely held in place for 15 correctly positioning the attachment in the normal operation of the machine.

In its preferred form, the attachment holder comprises a substantially flat plate preferably having a suitable work-engaging 20 element, such as a braid-guide, formed integral therewith and provided at one side of said element with a pair of spaced and downwardly offset fastened hooks disposed at one side of and directed oppositely from 25 said element with their backs resting against the edge of the sewing machine throat-plate which the body of said plate overlies and their recesses entered by the bed-plate slide whose adjacent marginal portion is over- 30 hung by a portion of the holding plate. By such construction, the attachment may be applied by merely placing it upon the throat-plate with its hooks depending below the adjacent edge thereof and the bed-plate 35 slide then moved up into the hooks to press them into contact with the adjacent edge of the throat-plate, whereby the attachment is accurately located relatively to the stitch-forming mechanism and is securely held in 40 position with parts thereof resting upon the upper face of the throat-plate and slide-plate, respectively, at opposite sides of the fastening means by which it is confined thereon. At the side opposite the fastening 45 hooks the holding plate has preferably a depending steadyng stud or projection entering an aperture of the throat-plate remote from the needle-hole, whereby the attachment is located lengthwise of the edge of the 50 throat-plate, and the holding plate has at the edge adjacent the fastening hooks a tongue or extension slightly downwardly inclined and upturned at the extremity for engagement with the top of the bed-plate slide and 55 serving by said engagement, and with the

fastening hooks as fulcra, to press the opposite side of the holding plate firmly upon the throat-plate and insure engagement of the steadyng stud with the throat-plate aperture.

60 In the drawings, Figure 1 is a perspective view showing a portion of a sewing machine bed-plate with a braid-guiding attachment embodying the present improvement applied thereto. Fig. 2 is a perspective view of the attachment taken from the under side. Figs. 3 and 4 are respectively an edge view and a transverse sectional view of the attachment secured in position by means of the throat-plate and bed-plate slide. Fig. 5 is a 70 perspective view of a feed-dog cover-plate attachment embodying the present improvement in a slightly modified form.

The sewing machine bed-plate 1 is shown 75 formed with the usual recess cut away in its front end in which is secured by means of the screws 2 the throat-plate 3 provided with the needle-hole 4 and feed-dog openings 5. The needle-hole is entered by the usual reciprocating needle 6. Within the slideway 7 80 of the said recess is fitted the bed-plate slide 8.

The attachment holder is shown in Figs. 1 to 4 inclusive comprising a flat sheet-metal holding plate formed with a straight member 9 overlying the end margin of the slide-plate 8 and the bowed member 10 mainly overlying the throat-plate and embracing a closed space surrounding the needle-path. The member 10 near its junction with the member 9 is formed with depending or downwardly offset hooks comprising the shank portions 11, and the lateral spring-lips 12 with their free ends extending toward the outside edge of the straight member 9, 90 these hooks being struck from and formed integral with the body of the holding plate.

The member 10 has formed centrally of its length on its under face the steadyng stud or projection 13 which enters an aperture 14 of the throat-plate 3 disposed remotely from and laterally of the needle-hole 4. The straight member 9 has upon its edge farthest from the bowed member 10 a tongue or extension 15 which is slightly dished to form an inclined portion adjacent the member 9 and an upturned extremity adapted for engagement with the forward edge of the slide-plate 8 to be deflected upwardly so as to slightly lift the member 9 upon the fas- 110

tening hooks as fulcra and thereby yieldingly press the member 10 upon the throat-plate to insure the maintenance of the stud 13 within the throat-plate aperture 14 and 5 the body of the holding plate in contact relation with the upper face of the throat-plate.

In Figs. 1 and 2, the member 9 is shown provided with an inwardly extending arm 10 16 having at its inner extremity and in alinement with the needle-hole 4 the braid-guide 17 in the form of a channel open at the bottom with a central rib depending into said channel, as described more particularly in 15 connection with my application Serial No. 782,629, filed August 2, 1913. The member 10 is provided at one side with an elongated aperture 18, upon one side of which is an upwardly extending guide-loop 19 through 20 which the braid may be directed to the guide-channel 17.

In the use of the attachment, the bed-plate slide 8 having been retracted, the holding plate is placed upon the throat-plate 25 with the member 10 overlying the latter and the member 9 disposed slightly beyond the lateral edge of the same and the backs of the shank portions 11 of the fastening hooks resting against the edge of the throat-plate and the stud 13 in register with the throat-plate aperture 14. The work-engaging element 17 thus assumes its correct operative position in alinement with the needle-path, as represented in Fig. 1. The 30 slide-plate 8 is then advanced into operative position, its forward edge engaging the tongue 15 and slightly elevating it and then entering the fastening hooks whose slightly dished spring-lips 12 snugly and yieldingly 35 embrace the marginal portion of the slide-plate while the forward edge of the latter clamps the shank portions 11 of the hooks against the adjacent edge of the throat-plate 3, by means of which the holding plate is 40 firmly secured in position and is caused to cling closely to the face of the throat-plate under the resilient action of its component members.

The shank portions 11 of the hooks, in 45 their engagement with the edge of the throat-plate, constitute positively acting positioning elements arranged respectively in advance and rearward of the steadyng stud and the work-engaging element relatively 50 to the direction of alinement of the hooks to prevent the lateral shifting of the attachment plate, while the lips 12 of the fastening hooks act in conjunction with the overhanging portion of the plate, including 55 the dished tongue 15, as opposed clamping means for gripping the end portion of the slide-plate at the side of the work-engaging element opposite the steadyng stud. As 60 will be observed, the upper and lower parts 65 of these clamping means are adapted for en-

gagement only by the movable slide-plate with which they are entirely out of contact so long as the slide-plate is retracted.

In the form of the attachment shown in Fig. 5, the body of the holding plate comprises a substantially semi-circular disk having the central and slightly raised circular work-engaging member 20 serving as a feed-dog cover-plate formed continuously with the bowed portion 3 of the holding plate. In this form of the attachment the work-engaging member is arched similarly to that of the attachment forming the subject of the United States Patent to Charles Stafford, No. 937,112, of October 19, 1909. 70 The portion 3 is provided along its alined straight edges with the downwardly offset or depending hooks 11 12 extending outwardly therefrom and the steadyng stud 13 struck therefrom as in the form of the 75 improvement represented in the other figures of the drawing. The work-engaging member 20 has a central needle-hole 4 and an outwardly projecting tongue or extension 15' similar to that previously described. 80 In this form of the improvement the straight member 9 carrying the tongue is omitted as the work-engaging member 20 is of such form as to readily sustain the same in the same relation to the fastening hooks 85 11 12 and the stud 13 as in the other form of 90 the improvement.

It will thus be seen that the essentials of the attachment holder are the same for the 95 various kinds of work-engaging elements 100 usually sustained by this class of holders, their form and character being determined by the function which they are required to 105 perform. In any event, the fastening hooks are directed oppositely from the position of the work-engaging element, that is, they project in a direction away from the position which such element occupies in the 110 contour of the plate, while the latter extends above and beyond the throats of the hooks, 115 afforded by the lips 12 and their shank portions, and in the same direction so as to act in conjunction with said lips in gripping the margin of the slide-plate 8. The overhang of the plate relatively to the hooks 120 thus operates to hold the attachment-plate flat upon the throat-plate or work-support and thereby maintain the straight steadyng stud 13 within its aperture 14, this stud being confined within the area of the aperture 120 so as to be readily inserted within and withdrawn from the latter without tilting or otherwise manipulating the attachment for the purpose.

The tongue or extension 15 is a desirable 125 addition to the holding plate in insuring its requisite contact relation with the face of the throat-plate, but it is evident that the character of the fastening hooks 11 12 will have a material influence upon the proper 130

holding of such plate, and that such tongue or extension is not therefore indispensable.

The substantially crescent-shaped attachment holding plate of my pending application Serial No. 782,629, while effective in properly sustaining the work-engaging element, has a disadvantage in that in the application of the attachment to the throat-plate, it must be tilted in opposition to the 10 spring holding hooks embracing the edge of the throat-plate for registering the steadyng pin or stud with the throat-plate aperture, and the holding arm for the work-engaging element must be sprung upwardly 15 to escape interference with the feed-dog which is lifted when the needle is elevated for introduction of the attachment. According to the present improvement, the attachment is applied to the throat-plate in 20 perfectly flat condition, the fastening hooks being wholly disengaged from the part which they normally engage until the attachment is properly positioned, when the device is secured in place without substantial 25 distortion of its fastening means and the liability of permanent bending and consequent impairment of their effectiveness.

From the foregoing description, it is evident that the present improvement is not 30 limited to the specific form and construction of the holding plate and its accessories herein shown and described, but is susceptible of material modification within the scope of the invention.

35 Having thus set forth the nature of the invention, what I claim herein is:—

1. A sewing machine attachment comprising a plate carrying a work-engaging element and having at one side of said element a depending straight steadyng stud or projection and at the opposite side thereof a depending fastening hook extending in a direction away from said work-engaging element, a portion of said plate extending 45 beyond the throat of said hook and in the same direction for cooperation with the latter in clamping the attachment in place.

2. A sewing machine attachment comprising a plate carrying a work-engaging element and having at one side thereof a depending steadyng stud and at the other side thereof opposed clamping elements adapted to engage opposite faces of the usual slide-plate and including yielding hooks arranged 55 remotely from each other and in a line and similarly directed transversely of said line and away from said work-engaging element and said steadyng stud.

3. A sewing machine attachment comprising a plate carrying a work-engaging element and having at one side of said element a depending straight steadyng stud or pro-

jection and at the opposite side thereof a depending fastening hook extending in a direction away from said work-engaging element, said plate being provided with a rounded tongue extending downwardly and beyond the throat of said hook in the same direction for coöperation with the latter in clamping the attachment in place. 70

4. In combination with a sewing machine throat-plate formed with a needle-hole and with an aperture remote therefrom, an attachment comprising a holding plate partially overlying said throat-plate and provided with a work-engaging element and with fastening hooks adjacent and extending away from the same and disposed within the contour of and offset from the lower face of said plate, said holding plate being 80 provided with a steadyng projection entering and wholly confined within the area of the aperture of said throat-plate, and a slide-plate also partially overlaid by said holding plate and whose edge is adapted to enter 85 said hook and grip the shank thereof against the adjacent edge of the throat-plate.

5. In combination with a sewing machine throat-plate formed with a needle-hole and with an aperture remote therefrom, an attachment comprising a holding plate partially overlying said throat-plate and provided with a work-engaging element and with fastening hooks adjacent and extending away from said element and offset from 90 the lower face of said plate, said holding plate being provided at one side remote from said hooks with a steadyng projection entering the aperture of said throat-plate and at the opposite side of said hooks with a 95 downwardly rounded tongue, and a slide-plate also partially overlaid by the holding plate and engaged by said tongue and whose edge is adapted to enter said hook and grip the shank thereof against the adjacent edge 105 of the throat-plate.

6. A sewing machine attachment comprising a plate carrying a work-engaging element, and having at one side thereof opposed clamping elements adapted to clamp 110 opposite faces of the usual sewing machine slide-plate, said clamping elements including yielding hooks bent downwardly and arranged remotely from each other, and having their beaks similarly directed away from 115 said work-engaging element and transversely of a line connecting said hooks.

In testimony whereof, I have signed my name to this specification, in the presence of two subscribing witnesses.

JOHN D. KARLE.
